Term of patent 14 years

(Cl. D72—1)

Fig. 1

Fig. 2

Fig. 3

Figure 1 is a perspective view of a chime signal showing my new design.

Figure 2 is a cross sectional view taken on the line 2—2 in Figure 1 illustrating the configuration of the front thereof.

Figure 3 is a fragmentary cross sectional view taken on the line 3—3 of Figure 2.

The top and the other side of the chime signal not shown are plain.

I claim:

The ornamental design for a chime signal, substantially as shown and described.
